Specification for Design.

Patented Jan. 4, 1916.

Application filed October 5, 1915. Serial No. 54,284. Term of patent 7 years.

To all whom it may concern:

Be it known that I, CHARLES W. HARMAN, a citizen of the United States, residing at New Rochelle, in the county of Westchester, in the State of New York, have invented a new and original and ornamental Design for Spoons, Forks, or the like, of which the following is a specification, reference being had to the accompanying drawing, forming a part thereof.

Figure 1 is a plan view; and Fig. 2 is a cross section through the shank of the spoon, fork or the like, showing my new design.

I claim:

The ornamental design for a spoon, fork, or the like as shown.

CHARLES W. HARMAN.
